(57) **CLAIM**

The ornamental design for a pet ramp as shown and described.

DESCRIPTION

FIG. 1 is a top, front, left perspective view of a pet ramp showing my new design;

FIG. 2 is a bottom, rear, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, left perspective view of the pet ramp in a second configuration, for clarity of disclosure; and,

FIG. 10 is an enlarged view of portion 10 shown in FIG. 1. In the drawings, the broken lines depict portions of the pet ramp that form no part of the claimed design.

1 Claim, 10 Drawing Sheets
